ATTORNEY.

UNITED STATES PATENT OFFICE.

HERBERT W. DAGGS, OF CLEVELAND, OHIO.

TIME SWITCH.

Application filed September 12, 1924. Serial No. 737,329.

To all whom it may concern:

Be it known that I, HERBERT W. DAGGS, a citizen of the United States, residing at Cleveland, in the county of Cuyahoga and State of Ohio, have invented certain new and useful Improvements in Time Switches, of which the following is a specification.

This invention relates to improvements in time switches having for an object to provide a structure such as will permit ready access to any of the working parts.

Another object is to provide a time switch having a sectional housing which may be readily separated and when assembled will provide a moisture proof protector for the working parts of the switch.

A further object is to provide a time switch housing in which the base portion and junction box are formed as a unit and removably connected to a front plate.

It is also an object to provide in a time switch of this character having a connection between the rotatable switch and the switch operating mechanism, a connection such as will eliminate fusion of the delicate parts in the event of an overcharge of current.

Other objects will be in part obvious and in part pointed out hereinafter.

In order that the invention and its mode of operation may be readily understood by persons skilled in the art, I have in the accompanying illustrative drawings, and in the following detailed description based thereon set out the preferred embodiment of the same.

Figure 1 is a front elevation of a time switch constructed in accordance with my invention;

Figure 2 is a side elevation thereof;

Figure 3 is a vertical longitudinal section thereof;

Figure 4 is a detail showing the means for providing moisture proof joints or connections between the parts making up the time switch housing;

Figure 5 is a plan view of the interior of the base portion of the housing.

Figure 6 is a view illustrating the connection between the switch and switch operating mechanism by which fusing of the mechanism is eliminated.

Figure 7 is a detail perspective view of this connection; and

Figure 8 is a vertical longitudinal section-al view of the parts shown in Figure 7.

Having more particular reference to the drawings throughout which similar characters of reference designate similar parts, this improved time switch may be stated as comprising the usual switch operating mechanism M which includes an intermittently operable shaft S having connection with a rotatable switch R as shown in Figure 3. This mechanism as shown is supported upon a set of spaced posts 10 which are integrally cast with the base portion 11 of the switch housing.

Broadly stated, this housing comprises a base and top or front cover plate inter-connected by means of a side wall whose open ends are snugly fitted into channels formed in the base and front portions.

The base portion 11 is provided with an upstanding peripheral wall 12 whose inner face 13 extends to a point beyond the outer corner of said wall, thereby providing a rib as shown in Figures 3 and 4. Between the inner and outer edges of the peripheral wall 12 I form a channel 14 which is substantially V-shaped, the rib 13 forming the longitudinal inner wall of the channel. At one end an apertured ear 15 is cast integral to provide means for hanging the time switch upon a support. As shown in Figure 3, the base portion 11 is extended at one end beyond the peripheral wall 12 to form the base of a junction box 16 . The outer wall 17 of the peripheral channel forms one upstanding wall of the junction box, the side walls 18 being formed or cast integral with said outer wall 17 .

The top and end of the junction box are closed by means of cover plates 19 and 20 respectively, these plates being secured in position by means of machine screws or the like. This junction box is designed to serve as a point of connection between the wires carried by the time switch and those coming in from the power lines.

A set of spaced openings 22 is arranged as shown in Figure 3 to provide connection between the main housing and the junction box. As illustrated, a set of upstanding apertured bosses 23 is provided and designed to receive the heads of connecting bolts or rods 24 whose outer ends are threadedly engaged in sockets carried by the top or outer cover plate 25 .

This top or outer cover plate 25 is provided with a channel 26 and long and short walls formed similarly to those of the peripheral wall 12 , carried by

the base. This top plate is also provided with a central opening 27 which is closed by means of a closure comprising a glass plate 28 arranged in an open frame 29 which as shown in Figure 1 is hinged at 30 to the cover or top plate 25. A locking screw 31 is arranged opposite the hinge so that the closure may be locked in engagement with the top plate 25. To insure against entry 10 of moisture into the housing, I provide a rubber packing 32 between the top or cover plate 25 and the end closure, this feature being shown in Figure 3 of the accompanying drawings.

15 An open ended shell or wall 33, preferably formed of sheet steel or the like, is arranged with its edges snugly fitted into the peripheral channels of the base and top or cover plates. These channels as shown are 20 provided with a packing strip 34 which is preferably formed of rubber so that it will snugly engage the walls of the channels and the edges of the shell 33, thereby absolutely preventing entry of moisture into the time 25 switch housing.

It is understood that at times it is necessary to have access to the time switch and the mechanism which moves the rotatable switch. Heretofore this has been extremely 30 difficult and it is my object to facilitate adjustment of these parts through providing a structure made up of separable parts. This is accomplished without forming a number of joints which would ordinarily 35 admit moisture or the like to the interior of the housing.

Heretofore, in connecting the rotatable switch and switch operating mechanism, the usual porcelain finger piece has been removed and a short metal shaft arranged to form direct connection between this mechanism and the spindle of the switch. This structure is extremely undesirable in that an over charge of current coming into the switch naturally passes on into the mechanism and fuses or burns out many of the delicate parts, thereby necessitating loss of time and money in repairs. I overcome 40 these objections through providing a connection as shown in Figures 6, 7 and 8, rendering unnecessary, the removal of the usual porcelain finger piece.

I loosely mount upon the inner or lower squared end 35 of the switch operating shaft 50 S, a yoke member 36 which as shown is substantially inverted U-shaped and includes pairs of spaced legs 37 which engage over the longitudinal side faces of the porcelain finger piece F. The usual porcelain finger 55 piece of a rotatable switch is enlarged centrally and it is for this reason that the pairs of spaced legs 37 are formed, it being obvious that through this formation the legs

will rather snugly engage adjacent the end portions of the finger piece.

65

It is quite apparent that through employing a connection of this type, an overcharge of current coming into the switch will have no effect whatsoever upon the switch operating mechanism since the porcelain finger 70 piece F will serve as an insulator, thereby preventing passage of the current to said mechanism.

As illustrated in Figures 3 and 5 I have provided in one side of the base portion an 75 opening 38 designed to permit insertion of oil which will saturate a sponge 29 and in turn oil the switch operating mechanism and relieve the interior of the switch housing of dampness or moisture. It is quite obvious 80 that through the construction heretofore described I have provided a time switch of strong construction and one which will be entirely reliable.

Manifestly, the construction shown is capable of considerable modification and such modification as may fall within the scope 85 of my claims, I consider within the spirit of my invention.

90

I claim:

1. A sectional time switch housing comprising a back plate having a continuous channeled peripheral outwardly extending wall, a portion of the lower end of said base being extended to form the base of a junction box, a set of supporting posts integral with the inner face of the back plate, a packing arranged in the channeled walls, walls cast integral with and at one end of the base plate to form sides of the junction box, an 100 open ended shell having the walls forming one end snugly engaging said packing material, a front plate having a channeled peripheral outwardly extending wall, a packing material in said channeled wall to 105 engage the outer end of said shell, and bolt means within the housing for separably inter-connecting the back and front plates.

2. A sectional time switch housing comprising a back plate and a front plate having relatively aligned channeled peripheral walls formed integrally therewith, a packing material set into the channeled walls, an open ended shell having its end walls 110 snugly engaging the packing material, bolts 115 arranged within the housing to separably inter-connect the back and front plates, said front plate having an opening, a closure hinged to the front plate to cover said opening, a compressible packing arranged between the cover and front plate and supporting posts integrally formed on the back plate and extending toward the front plate.

In testimony whereof, I affix my signature.

HERBERT W. DAGGS.
